UNITED STATES PATENT OFFICE.

GEORGE W. NALL, OF FIELD CREEK, TEXAS.

FURNITURE-BRACE.

No. 802,586.

Specification of Letters Patent.

Patented Oct. 24, 1905.

Application filed April 11, 1905. Serial No. 254,992.

To all whom it may concern:

Be it known that I, GEORGE W. NALL, a citizen of the United States, residing at Fieldcreek, in the county of Llano and State of 5 Texas, have invented certain new and useful Improvements in Furniture-Braces, of which the following is a specification, reference being had therein to the accompanying drawings.

10 My invention relates to furniture-braces, one of the objects being to provide a device of the character described that shall be simple and inexpensive in construction and easy of adjustment and operation and whereby the 15 slack in wires used in strengthening and bracing the side rails or frame of a bed, chairs, or other furniture may be taken up and the wires tightened.

Other objects and advantages of my invention as well as the structural features by 20 means of which said objects are attained will be made clear by an examination of the specification taken in connection with the accompanying drawings, in which the same reference-numerals indicate corresponding portion throughout, and in which —

25 Figure 1 is a perspective view of the frame of a bed provided with bracing-wires and showing my device in operative position on 30 the wires. Fig. 2 is a top plan of the bottom plate. Fig. 3 is a bottom plan of the top plate, and Fig. 4 is a cross-section lengthwise through the center of the device.

35 1 designates the frame of a bed, 2 the braces, and 3 the bottom plate of my tension device, which is provided with the grooves 4, extending diagonally across said plate and in which the wires 2 rest, said plate being also provided with the vertical projections 5 on 40 each side.

45 6 designates a top plate formed to fit upon the bottom plate between the vertical projections 5. This top plate is provided with four short grooves 7, leading out of a cavity 8 for the reception of the wires where they cross at the center of my device and permitting the top plate to fit down snugly upon the bottom plate when my device is placed upon said wires. Both the top and bottom plates are 50 provided with openings 9 to admit the threaded set-screws 10, said openings 9 in the bottom plate being threaded to allow the top plate to be screwed down tightly thereon.

In operation the bottom plate 3 is placed

against the wires in such manner that a wire 55 rests in each groove 4. The top plate is then placed over the wires, so that at the point of crossing they rest in the shorter grooves 7 and the cavity 8. The top plate is then screwed partially down, but not sufficient to press 60 tightly upon the wires. The slack in the wires is then taken up by moving the device lengthwise upon the wires in either direction, and the tightener is then securely held in such position by screwing the top plate down 65 tightly upon the bottom plate by means of the set-screws.

Having thus described my said invention, what I claim as new, and desire to secure by Letters Patent of the United States, is —

70 1. A tension device for furniture, a lower plate, a vertical projection formed integral with each side of said plate, grooves extending diagonally across the plate, a top plate having a cavity in the center thereof and grooves 75 leading out of said cavity and terminating on the surface of the plate, and a plurality of set-screws arranged to adjustably secure the plates together, substantially as described.

75 2. A tension device for furniture, a plate having grooves extending diagonally across the upper surface thereof, a vertical projection formed integral with each side of said plate, an auxiliary plate adapted to rest upon the first-mentioned plate between the vertical 80 projections, said auxiliary plate having a cavity in the center thereof and grooves leading out of said cavity and terminating on the surface of the plate, and set-screws passing through apertures in said plates and adapted to adjustably secure the same together, substantially as described.

85 3. A tension device for furniture comprising an upper and a lower plate adjustably secured together, one of said plates being provided with grooves extending diagonally across the same, and a vertical projection formed integral with each side of the lower plate and between which the upper plate is adapted to rest in position, substantially as 90 described.

95 In testimony whereof I hereunto affix my signature in presence of two witnesses.

GEORGE W. NALL.
